UNITED STATES PATENT OFFICE.

JOHN G. NEWELL, OF NEW HAVEN, CONNECTICUT.

BURGLAR-ALARM.

SPECIFICATION forming part of Letters Patent No. 325,961, dated September 8, 1885.

Application filed February 9, 1885. (No model.)

To all whom it may concern:

Be it known that I, JOHN G. NEWELL, of New Haven, in the county of New Haven and State of Connecticut, have invented a new Improvement in Burglar-Alarms; and I do hereby declare the following, when taken in connection with accompanying drawings, and the letters of reference marked thereon, to be a full, clear, and exact description of the same, and which said drawings constitute part of this specification, and represent, in—

Figure 1, a perspective view of the alarm full size; Fig. 2, a transverse section through a door and its jamb, showing the alarm as applied; Fig. 3, a vertical central section enlarged.

This invention relates to the construction of a device to be attached near a door or other opening, whereby when the door, or whatever it may be that closes the opening is opened or moved an alarm will be sounded; and the invention consists in the construction herein-after described, and more particularly recited in the claim.

25 A represents a tube, to one end of which a cap, B, is screwed, and to the other end a similar, cap, C. In the tube a spindle, D, is arranged to work free longitudinally. At one end the tail E of the spindle extends out 30 through the cap C, the tail of the spindle being of less diameter than the body of the spindle, and so as to form a shoulder, a, thereon.

35 Between the shoulder and the cap, through which the tail passes, a spiral spring, F, is introduced around the tail, and so that one end rests against the cap and the other on the shoulder, the tendency or action of the spring being to force the spindle toward the opposite end of the tube into the cap B.

40 In one side of the tube a slot, b, is formed, through which projects a finger, G, from the spindle, and so that the spindle may be moved longitudinally in the tube by means of the finger G serving as a handle for that purpose. 45 At the end of the slot b next the spring a transverse slot, d, is cut, and so that the spindle may be forced against its spring and compress the spring, and when so compressed the finger be turned into the notch d, as in Fig. 3, 50 and so as to hold the spindle in that position.

The cap B is removable for the insertion of a percussion pellet, the pellet being indicated at e, Fig. 3. The cap replaced serves as an anvil, so that when the spindle shall be turned, to bring the finger into line with the slot, the 55 spring will forcibly drive the spindle toward the anvil or cap B, and crush the pellet, producing an explosion, which will give an alarm.

The tube is provided with a thin sharp blade, H, which may be forced into the jamb near a 60 door, as seen in Fig. 2; or, instead of a blade, it may be a screw-shank to be driven into the jamb, as in Fig. 2.

The alarm is applied to the jamb near the door, I, Fig. 2, representing the jamb, and L 65 the door. The finger G, when turned into its notch, stands in the path of the opening door, and so that as the door is opened it must strike the finger, and in so doing will throw the finger into the slot, leaving the spindle 70 free, and so that the spindle may be discharged to produce the explosion. Then, when it is desired to reset the alarm, a new pellet is applied, and the spindle drawn and caught at its cocked position, which brings the finger 75 into the position seen in Fig. 2, and again in the path of the opening door.

This device is so small as to be conveniently carried in the pocket for the use of travelers and others, Fig. 1 representing the device in 80 full size, and having been applied and performed its office in one place it may readily be removed and retained for use in another place, the blade or screw making the device readily attachable or detachable wherever the 85 alarm may be desired.

The representation of the alarm as applied to a door-jamb will be sufficient to enable those desiring the use of such an alarm to apply it to windows, or wherever a temporarily- 90 closed opening is required to be protected.

In order that a slight rotation only may be necessary for the spindle to take the finger G out of the path of the door, I make the slot b diagonal, inclining away from the notch d and 95 away from the door, and so that as the spindle moves in the cylinder the spiral slot, acting upon the finger, will give to the spindle a partial rotation, and thus throw the finger farther around than when it left the notch d; but 100

the slot may be parallel with the axis of the tube.

The alarm may be applied as a permanent attachment. Where it is desired, however, to so attach it, I prefer to omit the blade or shank, and apply ears to the cylinder, as indicated in Fig. 3, through which screws may be introduced to secure it.

I am aware that an alarm consisting of a tube, with a spindle-like handle therein, and a finger extending from the hammer through an L-shaped slot in the tube, is a well-known device; but this I do not claim, the essential feature of my invention being the diagonal or spiral slot which extends from the transverse notch *d*, and whereby the longitudinal movement of the hammer under the action of the spring imparts to the hammer a rotary move-

ment to turn the locking-finger completely out of the path of the opening door.

20

I claim—

The combination of the tube *A*, provided with the removable cap *B* at one end, and constructed with a diagonal slot, *b*, the said slot turned transversely at its end to form a notch, *d*, the spindle *D*, arranged in the cylinder for free longitudinal movement, spring *F* in the cylinder adapted to force the spindle toward the removable cap, the said spindle provided with a finger, *G*, extending through the said slot, the said tube constructed for attachment substantially as described.
